PAPERBOARD CONTAINER AND METHOD OF
MAKING SAME

Arthur J. Weiss, Englewood, N. J., and Harry J. Rossi, Bronx, N. Y., assignors to Robert Gair Company, Inc., New York, N. Y., a corporation of Delaware

Application August 23, 1938, Serial No. 226,226

15 Claims.

(Cl. 229—14)

The present invention relates to an improvement in paperboard cartons and is especially directed to a collapsible or knock-down carton in which an inner, waterproof liner is used to enable the package to be used for holding, shipping and dispensing liquids, frozen food products and other articles of commerce.

Another feature of advantage lies in the method of introducing the liner into the carton, filling, closing and sealing the liner, to effect a liquid-tight closure of the liner, after filling. The present improved carton may be used to package any material or liquid, other than those above indicated, but the special use for the herein carton is for liquids.

Another feature of advantage lies in the cooperation of the liner mouth and the closing means of the carton, as will hereinafter appear in detail, to obtain a closure whereby to mechanically reinforce the liner mouth against hydrostatic bursting pressure, to prevent its accidental rupture.

One of the cartons herein shown, is similar to the carton shown in the pending U. S. patent application Serial No. 197,973, filed March 25, 1938, in the name of Arthur J. Weiss, but the coaction of said carton, in the present disclosure, effects a method of sealing a lined container therein, which is novel and effective.

30 The foregoing and other features of advantage will be apprehended as the herein description proceeds, and it will be obvious that modifications may be made in the structures and steps of procedure, as herein disclosed, without departing from the spirit hereof or the scope of the appended claims.

In the drawing,

Fig. 1 is a flat layout of one form of blank used in forming the carton of the herein improvement;

40 Fig. 2 is a perspective view of the carton of Fig. 1, partially assembled with its bag-like liner, with parts broken away for better understanding;

45 Fig. 3 is a perspective view of one form of the bag-liner, before introduction into the carton or container;

Fig. 4 is a bottom view of the container of Fig. 2, closed;

50 Fig. 5 is a fragmentary side view of the bottom of the container of Figs. 2 and 4, shown closed;

Figs. 6, 7, 8 and 10 are fragmentary side views, in elevation of the top closure of the bag-liner and carton in successive steps of closing;

55 Fig. 9 is a fragmentary view in front elevation,

of the top end of the bag and container closure, partially fragmented, showing the position of the coacting parts, as disclosed in Fig. 8;

Fig. 11 is a fragmentary plan view of the top portions of Fig. 2, closed;

Fig. 12 is a blank layout of a modified form of carton blank, underlaid by a flat liner-forming blank; and

Fig. 13 is an enlarged, transverse, sectional view of the blank of Fig. 12, after folding and before final gluing.

The blank of the container as shown in Fig. 1, comprises two body-forming front and rear panels 4 and 2 respectively, separated from each other by a body-forming side panel 3, by score lines c and d. Panel 4 at one end carries a foldable closing flap 22, defined therefrom by a common score line e, said flap 22 having an extending latch tongue T' at its outer edge.

Front body-forming panel 4, has also, at its opposite end a foldable top end closing flap 6, defined from panel 4 by a common score line f, said flap having a latching spring slit S within its confines, to coact with locking tongue T on panel 2, when this end of the container is snapped closed, to form a top end locking closure for the container.

The side-forming panel 3 has on its opposite ends, Fig. 1, diagonally scored, inclosing, foldable end flaps 7—15—16 and 20—21, the flap 30 20—21, being a bottom closing, diagonally scored member, and being defined from panel 3 by the common score line e. Flap 20—21 is traversed by the single diagonal scored folding line k. The opposite end of the top forming infolding flap 35 7—15—16, which is defined from panel 3 by the common score line f, is traversed by two diagonal fold lines i and j, which define a triangular or infolding bellows fold, formed by the triple triangular sub-flaps 7—15—16.

40 Main front-forming body panel 2, at its bottom end closure portion is provided with an end closing flap 19, which is defined from front-forming panel 2, by common score line e, and is defined from diagonal side closing sub-flaps 20—21 and 45 17—18, by folding score lines c and b, respectively. End closing flap 19 is also provided with a latch spring slit S', to coact with tongue extension T', when the bottom is closed.

The opposite top end of rear panel 2 is provided with a liner-clasping top end closing flap 8—9—10, this being defined from front panel 2 by common score line f, this, in turn being traversed by folding score lines h, f' and f'', the lines f' and f'' being interrupted at their mid- 55

section by a cut spring latch T, which coordinates with the snap latch slit S to lock the upper or top end of the container when the flaps are closed. The score lines h and f'-f" run parallel with score line f.

The side-forming body panel 1 is defined from the rear body-forming panel 2, by a score line b, and this side-forming panel is provided at its opposite ends by diagonal and bellows-like end closing flaps 17-18 and 11-13-14, which are similar to those described for side-forming panel 3. Bellows-forming inclosing end flap 11-13-14 is defined from panel 1 by the common score line f, and it is provided with triangular score lines o and p, and at the opposite end thereof the infolding flap 17-18 is provided with a single diagonal score line r, said flap 17-18 being defined from panel 1 by score line e.

There is further provided on the blank, Fig. 1, a glue lap 5', this being defined from panel 1 by a score line a. One end of flap 5', at f, extends over and is defined from flap 13 by common score line a.

In assembling the blank of Fig. 1 into a flat, collapsible, erectable container, the glue lap 5' is folded upwardly, as viewed in Fig. 1, on score line a, and then downwardly upon the face of side panel 1, and the exposed face of lap 5' is then glued, and the panels 3 and 4 are bent upwardly and downwardly on score line c, as viewed in Fig. 1, and the lap 5' is glued to the exposed marginal edge of panel 4. The container so formed is then ready to ship, knocked down, to the goods manufacturer, to be erected, filled and sealed, and thence shipped to the distributor, for eventual sale to the consumer.

After the manufacturer receives the packages, he erects the container, by first opening it to a rectangular position, on the score lines a, b, c and d, then the bottom is closed by bending inwardly, simultaneously, the end closing flaps 17-18 and 20-21. This action draws the end flap 19 to closing position, and then the flap 22 is infolded and pressed downwardly until the tongue T' snaps into the tongue latching slit S'. This completes the bottom locking end closure, as shown in Figs. 4 and 5.

Then the liner C' shown in perspective in Fig. 3 is entered into the interior of the erected container as shown in Figs. 2 and 6. This liner may be of any suitable pliable material, such as a waxed paper, but preferably it is made up of a clear cellulosic pliable material, which may be made up in the form of an open ended bag, as shown in Fig. 3, with bellows-folded sides B-B, which are infolded to enable the bag to be shipped flat, in packages, the bottom E of the bag being sealed shut.

The bag is inserted in the outer container, as indicated in Fig. 2, leaving an upwardly externally extending end G, and is then opened, and filled with a sufficient quantity of desired material or liquid, the bag illustrated being so made as to be liquid and leak proof.

The next action is to close the bag and container simultaneously, to effect a liquid and leak proof sealing of the bag mouth, and to finally interengage and lock the extending bag mouth by infolding the bag mouth with the portion 10, and then completing this enclosure by latch locking. It makes no difference in the final mouth sealing and locking, whether the steps about to be described are performed by hand or by an automatic sealing device, but it is intended to

perform all of the erecting, lining and container closing by a machine devised for this purpose.

After the bag has been inserted in the container and filled, the opposed top, main end closing flaps 6-8 are simultaneously moved inwardly towards meeting position by simultaneously pressing the opposed flaps 7 and 11 towards each other. Owing to triangular scoring on these flaps, which form the sub-flaps 15-16 and 13-14, this action causes the flaps 7 and 11 to close in the top end of the bag and reforms the bellows-fold B of bag on both sides, as illustrated in Figs. 2 and 6, and, at the same time, to draw the opposed flaps 6 and 8 toward each other, this step also gradually bringing the open sides of the bag together, until finally, when this first step of closure is completed, the bag mouth is pinched shut, as shown in Fig. 7, the outer edge of the flap 6 and the folded edge formed by score line h, flap 9-10 being bent backwardly on the line h, and the flaps 6, 7, 8 and 11 then act as pincers to hold the bag mouth closed on all four sides, with the exposed compressed portion G thereof extending above the confines of the closed flaps 6 and 8. After this step has been performed the closed bag mouth G, Fig. 7, is then tightly sealed by pressing opposed heater jaws H-H on opposite sides of the closed mouth end. These jaws are electrically heated, and when applied under heat, cause a cement, previously applied to the inner faces of the bag mouth, to soften and then to set, leaving the bag mouth completely sealed in a liquid-proof manner. After the cement has been softened, the edge h of flap 8 and the edge of flap 6, retain the seal cemented bag mouth until the cement has set. After the cement has set, for the final closing of the top to lock the closure and to reinforce the cemented seal against rupture, the flap portion 9-10 is bent up parallel with the upstanding bag mouth G, Figs. 8 and 9, and the top portion of the bag mouth is folded and creased into an end lap G', and the flap portion 10 is folded thereover on score h, leaving the latch tongue T, upstanding. Then the flap 8-9 is folded down onto flap 6, thus providing a second fold crease and the flap 8-9 is then pressed downwardly, springing the top closure flaps 8-9-10 and 6, until the latch tongue T springs or snaps under and into the slotted latch locking member S, as shown in Figs. 10 and 11, thus locking the top end closing flaps over the cemented bag mouth.

When and after the carton is erected, the webs 17, 18 and 20, 21 form a support for the flaps 19 and 22; and the tongue T' will snap under the tongue S' when the flap 22 is pressed on the flap 19. Said webs form a support cooperating with said inner flap 19 to prevent accidental depression of the flaps 19, 22 and to hold both flaps in normal latching position, and to prevent excessive undesired depression of the inner flap during said snapping.

In Fig. 12 there is shown a flat, paperboard blank for creating a slightly modified form of container. The blank is shown in full lines, and is underlaid by a registered, rectangular sheet of cellulosic liner-forming material C which may be affixed to the underface of the blank by gluing if desired. The container blank comprises two front and rear forming panels 4 and 2, respectively which are defined from one another by being scored from an intermediate side-forming panel 3, by score lines d and c, respectively. Front body panel 4 is provided with opposed end

flaps 6—6, which are defined therefrom by common score lines *f* and *e*. The said flaps are provided with slotted latch tongues S—S.

Side forming panel 3 is provided at each of its opposite ends with infolding top end closing flaps 15—16—7, these flaps being each provided with triangular score lines *o* and *p*, thus providing triangular sub-flaps 15, 16 and 7. These webbed flaps 15—16—7 are defined from panel 4 by common score lines *f* and *e*, and when infolded, form connected bellows-like pleated flaps.

Rear body-forming main panel 2 is defined from the side-forming panels 1 and 3, by score lines *b* and *c*, respectively, and on each of its opposite ends is provided with composite infolding end closing flaps 8—9—10, said flaps being defined from panel 2 by common score lines *f* and *e*. These closing flaps are traversed by a score line *h*, which is parallel to line *f*, to define sub-flap 8 from sub-flap 9, and sub-flap 9 is defined from sub-flap 10 by score lines *f'* and *f''*, intermediate of which is located a slotted cut spring latch tongue T.

Side-forming panel 1 is defined from rear panel 2 by a score line *b* and is defined from the glue lap 5 by score line *a*. Panel 1 is provided at its opposite ends with bellows-like end closing flaps 11—13—14 which are defined from panel by common score lines *f* and *e*, and are defined from each other by diagonal score lines *o—p*, to form connected sub-flaps 11, 13 and 14. These flaps when the container is erected, are opposed to the flaps 7—15—16, and they function the same as said latter flaps, as will be later discussed in detail.

Glue lap 5 is more extensive than the glue lap 5' of Fig. 1, and is provided with rectangular corner overlaps 12 at its opposite ends these being defined by common score lines *f*, *e* and *a*.

The cellulosic liner sheet C, Fig. 12, is flat, and not in a pre-formed bag structure as shown in Fig. 3, and as seen in Fig. 12, the sheet is slightly narrower than the length of panel 2 and its flaps 10, and length-wise it terminates at about the mid-section of glue lap 5, and at its opposite end extends beyond the limits of the blank thus to form a marginal extension around the edges of panels 3 and 4.

In assembling and erecting the container from the blank of Fig. 12, after the blank has the cellulosic sheet liner adhered thereto, the blank and sheet liner C, are then turned over to expose the lined blank surface face upwards, then glue is applied to the liner margin which covers the glue lap 5 and the glue lap margin *t*, and glue is also applied to the marginal face *m* of the liner at its opposite end, the panels 4—3 are then bent upward on score line *c*, and then bent down until the liner portion on panels 4—3 comes into contact with the liner face of panels 1—2. Then the glue lap 5 is bent upwardly and over and downwardly to bring its glued liner and flap portion *t* into over-folded contact with the glued liner margin *m* and the marginal edge of panel 4, as illustrated in the enlarged sectional view shown in Fig. 13, wherein the overlap described is shown before the final seal.

This structural assembly of the inner and container blanks lines the inner face of the container with a perfectly sealed, leak-proof inner liner, the jointure at the overlapped portions of the marginally adhered liner edges and the container-lap adherence forming an imperious joint.

The liner, as above described, forms an open ended, tubular formation, both ends being open,

and as the container is initially made flat, being folded on its score lines *a* and *c*, the container is thus erectable as described for the container of Fig. 2.

After the erection of the blank into rectangular container form, the end closing flaps and extended liner ends are closed and sealed in a manner exactly as described for the container of Fig. 1. In the erected container of Fig. 12, because of the similarity of the end closing flaps thereon, either end may be top or bottom.

In setting up, for filling and sealing the carton of Fig. 12, when closing the same manually, the container, with the front panel 4 is faced towards the erector, then the webbed side closing flaps 11—13—14 and 7—15—16, are infolded simultaneously, and this action simultaneously draws down the closing flaps 8—9—10, and this action after folding the portions 9—10 outwardly on score line *h*, is shown in Fig. 7, and from then on the sequence of steps of heat-sealing and final latching closure, after filling is identical with the steps shown in Figs. 7, 8, 9, 10 and 11. As will be apprehended both ends of the container of Fig. 12 are identically constructed and closed. This container, like the one shown in Fig. 3, is susceptible of either manual, or machine-actuated, filling, heat-sealing and closing.

Having thus described the invention what is claimed is:

1. A carton comprising opposite panels; inner and outer flaps foldably joining the panels, the inner flap extending partly across the carton; the outer flap having a fold line within and along the outer margin; and a liner for said carton having a closure portion received between said flaps and against the outer margin of the outer flap; said portion and outer margin being folded along the fold line in a position under the outer flap.

2. A carton comprising an outer flap having a fold line; and a liner for said carton having a closure portion received against the inner face of the flap; said portion and the part of the flap beyond the fold line being folded together along the fold line in a position under the outer flap.

3. A carton comprising opposite panels; inner and outer flaps foldably joining the panels; the inner flap extending partly across the carton and provided with a slit forming a longitudinal latch edge; the outer flap having a slit forming an outwardly projected longitudinal latch tongue; a liner for said carton, the upper portion thereof being folded flat and disposed between said flaps and against the outer margin of the outer flap; said portion and outer margin being folded along a longitudinal line under the outer flap, disposed to leave the latch tongue projected to engage under said latching edge.

4. A carton comprising opposite panels; inner and outer flaps foldably joining the panels, the inner flap extending partly across the carton; the inner flap being provided with a slit forming a longitudinal latch edge; the outer flap having an inner fold line substantially along the free edge of the inner flap, and having a slit forming an outwardly projected longitudinal latch tongue, and aligned longitudinal fold lines joining the slit; a liner for said carton, the upper portion thereof being high enough, when said portion and flaps are upright, to project beyond said aligned fold lines; said portion of the liner being received between said inner fold line and the inner flap and against the outer margin of the outer flap; said portion and outer margin being folded along

the alined fold lines in a position under the outer flap, leaving the latch tongue projected and engaged under said latching edge.

5. A carton comprising opposite main panels; spacing panels therebetween; inner and outer flaps foldably joining the main panels, the inner flap being adapted to extend half across the carton; the inner flap being provided near its mid-part with a slit forming a longitudinal latch edge; the outer flap having an inner fold line along the middle axis of the top of the carton, and having, at the mid-portion of its free margin, a slit forming an outwardly disposed latch tongue, and alined longitudinal fold lines joining the ends of the slit, whereby the margin may be turned under the flap, leaving the latch projected.

6. A carton as in claim 5 having a liner for said carton, the upper portion thereof being high enough to project beyond said alined fold lines when the outer flap is upright; whereby when portions of the adjacent liner are folded inwardly and said flaps are drawn downward, said upper portion will be received between said inner fold line and the inner flap, against the outer margin of the outer flap and is foldable with said outer margin along the alined fold lines to a position under the outer flap, leaving the latch tongue projected to engage under said latching edge.

7. A carton comprising opposite main panels; spacing panels therebetween; inner and outer flaps foldably joining the main panels, the inner flap being adapted to extend half across the carton; web extensions foldably joining the ends of the flaps and the spacing panels respectively, and each being divided into triangular middle and end sections which fold inwardly horizontally flat upon each other; the inner flap being provided near its mid-part with a slit forming a longitudinal latch edge; the outer flap having an inner fold line along the middle axis of the top of the carton, and having, at the mid-portion of its free margin, a slit forming an outwardly disposed latch tongue, and alined longitudinal fold lines joining the ends of the slit, whereby the margin may be turned under the flap, leaving the latch projected.

8. A carton as in claim 7 having a liner for said carton, the upper portion thereof being high enough to project beyond said alined fold lines; whereby when said extensions are folded inwardly, adjacent portions of the liner are folded inwardly, said flaps being drawn downward, causing said upper portion to be received between said inner fold line and the inner flap, against the outer margin of the outer flap and foldable with said outer margin along the alined fold lines to a position under the outer flap, leaving the latch tongue projected to engage under said latching edge.

9. A carton blank comprising main panels and a lap panel; spacing panels therebetween; inner and outer flaps integrally foldably joining said main panels respectively; the inner flap being half as wide as the intermediate panels; web extensions substantially as wide as the inner flap integrally foldably joining the ends of the inner and outer flaps and the respective spacing panels, and each being diagonally traversed by weakened lines extending from the respective inner corners of the web and flaps; the inner flap being provided near its mid-part with a slit forming a longitudinal latch edge near the inner edge of the inner flap; the outer flap being wider than

the intermediate panels and provided with a longitudinal inner fold line and at the mid-portion of its free margin with a slit having a longitudinal portion and angularly turned ends turned toward the inner edge of the flap to form a longitudinal latch tongue; the outer flap having alined longitudinal fold lines joining the ends of the slit.

10. A blank as in claim 9 having a thin pliable rectangular liner adhered on the blank and extending throughout the inner margin of the lap, and beyond said extensions and alined fold lines.

11. A carton having opposite panels having inner and outer flaps joined thereto, the outer flap having a fold line remote from the panel; and a liner for said carton the upper portion of the liner being adapted to extend beyond said fold line; the outer margin of the outer flap and said upper portion being folded along said fold line to a position under the outer flap with the fold of the upper portion between said margin and the outer flap.

12. A carton comprising opposite main panels; spacing panels therebetween; inner and outer flaps foldably joining the main panels, the inner flap being adapted to extend half across the carton; web extensions foldably joining the ends of the flaps and the spacing panels respectively, and each being divided, by score lines extending to the inner corners, into triangular middle and end sections which fold inwardly horizontally flat upon each other; the inner flap being provided near its mid-part with a slit forming a longitudinal latch edge; the outer flap having an inner fold line along the middle axis of the top of the carton, and having, at the mid-portion of its free margin, a slit forming an outwardly disposed latch tongue, and alined longitudinal fold lines joining the ends of the slit, whereby the margin may be turned under the flap, leaving the latch projected; and a thin pliable liner for said carton of the approximate shape of the interior of the carton and engaging the walls thereof, the upper portion of the liner being high enough at all sides to project beyond said alined fold lines when the flaps are upright.

13. A reclosable paper carton comprising opposite main panels; spacing panels therebetween; inner and outer flaps foldably joining said main panels respectively; web extensions foldably joining the inner flap and the respective spacing panels, and each diagonally traversed by a weakened line extending from the inner corner of the inner flap, whereby the web folds inwardly to form a resilient support under the flaps; said flaps being respectively provided near the mid-portion of the inner flap with interengaging latching means adapted to snap into latching engagement with each other when the mid-portion of the free edge of outer flap is sufficiently pressed downwardly and the inner flap is sufficiently thereby depressed.

14. A reclosable paper carton comprising opposite main panels; spacing panels therebetween; inner and outer flaps foldably joining said main panels respectively; web extensions foldably joining the inner flap and the respective spacing panels, and each diagonally traversed by a weakened line extending from the inner corner of the inner flap, whereby the web folds inwardly to form a support under the flaps; said flaps respectively being provided near the mid-portion of the inner flap with interengaging latching means adapted to snap into latching engagement with each other when the mid-portion of the

free edge of outer flap is sufficiently pressed downwardly and the inner flap is sufficiently thereby depressed; said support cooperating with said inner flap to prevent accidental depression of the flaps and to hold both flaps in normal latching position, to prevent excessive undesired depression of the inner flap during said snapping.

15. A paperboard box comprising an outer flap

having a fold line dividing said flap into outer flap portions adjacent to the fold line; and a liner for said box having a closure portion received against the inner face of the outer flap; said closure portion and one flap portion being folded together along the fold line in a position under the other flap portion.
